SUPPORT FOR WEFT REPLENISHING MAGA-
ZINES

Irving H. Verry, Worcester, Mass., assignor to
Crompton & Knowles Loom Works, Worcester,
Mass., a corporation of Massachusetts

Application April 15, 1936, Serial No. 74,519
Renewed September 16, 1937

10 Claims. (Cl. 139—232)

This invention relates to improvements in looms and it is the general object of the invention to provide a loom which may be readily convertible from an automatic weft replenishing loom operating with a plurality of weaving shuttles to a loom operating pick and pick with drop boxes on both ends and capable of accommodating a larger number of shuttles.

The class of goods which a textile mill is called upon to manufacture may vary considerably as to the variety of weft, the simpler fabrics calling for a comparatively small number of shuttles, in which case it is expedient to operate the loom automatically, and the fancier fabrics calling for a larger number of shuttles which cannot conveniently be replenished automatically by simple mechanism. It has been necessary heretofore to maintain a section of automatic looms to weave the simpler fabrics and maintain a second section of looms having drop boxes on both ends, to weave the fancier fabrics. It is an important object of my present invention to provide a loom having the automatic weaving instrumentalities in place when weaving simple box patterns, but capable of being swung to inactive position on the loom to permit the addition of drop boxes at the magazine end of the loom. The magazine is mounted so that it can be thrown up to a position where it will not interfere with the shifting of the shuttle boxes adjacent thereto.

The magazines of weft replenishing looms ordinarily include in their construction a foot to be bolted or otherwise secured to the loom breast beam, and furthermore, there is usually a brace between the top of the magazine and the loom arches to prevent undue vibration. It is a further object of my present invention to modify the top brace so that it can be used as a pivot about which the magazine can be swung to inactive position when the loom is converted from automatic to non-automatic pick and pick.

When the loom is weaving automatically the magazine is generally located with a portion thereof nearer the center of the loom than the adjacent ends of the arches. It is another object of my invention to provide a brace preferably so constructed as to permit an endwise sliding of the magazine away from the center of the loom so that the arches will not interfere with the magazine as the latter is pivoted to idle position. A still further object of the invention relates to connections between the brace and the magazine which permit the latter to be adjusted both vertically and horizontally with respect to the transfer position of the lay.

With these and other objects in view which will appear as the description proceeds, my invention resides in the combination and arrangement of parts hereinafter described and set forth.

In the accompanying drawings, wherein a convenient embodiment of my invention is set forth,

Fig. 1 is a front elevation of a loom having my invention applied thereto, the magazine being shown operative to effect automatic weft replenishment,

Fig. 2 is a view of the right end of the structure shown in Fig. 1 but with the magazine swung to idle position to accommodate a gang of shifting boxes similar to the set on the opposite end,

Fig. 3 is an end elevation looking in the direction of arrow 3, Fig. 1, the lay end and shuttle box being in section,

Fig. 4 is a perspective view of the magazine end of the lay adapted for weaving pick and pick, the magazine being shown in non-operative position,

Fig. 5 is a view looking in the direction of arrow 5, Fig. 2, indicating in full lines the arrangement for automatic and in dotted lines for pick and pick weaving,

Fig. 6 is a detailed vertical section on line 6—6 of Fig. 1, and

Fig. 7 is a detail plan in the direction of arrow 7, Fig. 5.

Referring to the drawings, I have shown a loom which is adapted for weaving either 4x1 or 4x4, that is, four boxes at one end and one at the other, or four boxes at each end, although the invention is not limited to the specific number of shuttle boxes set forth herein. The magazine is of the customary multicolor type and follows a construction which has gone into general use, being arranged to store four distinctive types of reserve weft bobbins which are drawn when needed for insertion into a selected depleted shuttle.

As shown in Fig. 1 the loom frame 10 supports a lay 11 having reed 12 and supported on swords 13 which move about a rocker shaft 14. The left end of the lay is provided permanently with a set of shifting shuttle boxes 15 having a plurality of cells, four in number in the present instance, and indicated at 16, 17, 18 and 19, respectively. These shuttle boxes may be positioned with respect to the shuttle race 20 of the lay by means of a box lifter rod 21 moved vertically by a chain 22 the position of which is determined by a pattern mechanism such as a Knowles head, not shown but well understood. A picker stick 23 is employed to pick from the left hand side of the loom as viewed in Fig. 1

any shuttle which is aligned with the shuttle race when the lay is approximately in mid position during its rearward travel. The left end of the loom may be of usual construction and 5 of itself forms no part of my present invention.

The right end of the loom is modified so that it can accommodate either a single shuttle box, or four shifting boxes, as desired. The lay has a lay end 30 which as shown in Fig. 1 is provided with a single shuttle box B formed preferably of a T-section 31, see Fig. 3. The shuttle S rests on the web 32 as a box floor and is limited as to rearward motion relatively to the lay by a box back 33 formed as part of the section 31. The 10 box back aligns with the reed 12 while the web 32 aligns with the shuttle race 20. The box 31 is held detachably to the lay-end by bolts 34. The web 32 may be provided with a slot 35 to permit discharge of a depleted bobbin from the 15 shuttle S.

The magazine M has inner and outer plates 40 and 41, respectively connected together by tie rods 42. Provision is made on the adjacent surfaces of the plates 40 and 41 for the storing 20 and downward feeding of a plurality of distinctive reserve bobbins, four in the present instance to correspond to the cells of the shifting boxes 15. A transferrer arm 43 and latch 44 operate in the usual manner to move a selected 25 bobbin from the giveways to the shuttle.

The magazine has a foot 45 which is mounted on a stand 46 the vertical web 47 of which is bolted at 48 to the loom frame. The web 47 and bolts 48 permit a limited vertical adjustment 30 of the magazine so that the giveways 49 and 50 which support a selected bobbin for transfer may be adjusted relatively to the shuttle S when the lay is in foremost position. The magazine is indicated semi-diagrammatically and 35 there has been omitted from the drawings the selector and indication storing mechanism. The weft detector D may be used as indicated in Fig. 5 and is mounted on a support 52 depending from the magazine.

45 For further details of the magazine and the weft detector reference may be had to Patent No. 1,030,748 to Ryon and No. 1,777,346 to Bergstrom.

My present invention includes an alteration 50 in the upper part of the magazine involving the addition of two links 60 having their forward ends pivoted and held fast with respect to one of the tie rods 42 by means of set screws 61, see Fig. 5. The other ends of the links 60 are pivoted to swing about a brace rod 62 the inner end 55 of which is supported by the forward arch 63 of the loom and the outer end of which is extended through the upper end of a brace 64. The lower end of the latter is bolted as at 65 to 60 a carrier 66 forming a fixed part of the loom structure, and as set forth in Fig. 4, supplying one of the bearings 67 for the top shaft 68 which drives the lay. As shown in detail in Fig. 6 the arch 63 is provided with a slot 70 extending horizontally and affording a horizontal adjustment for the position of rod 62, the adjustment being held by a lock nut 71. By the construction last described the rod 62 can be moved toward or from the front of the loom when it is necessary 70 to adjust the magazine in that direction to place the magazine correctly for transfer purposes. Slots 53 in foot 45 permit a back and forth adjustment of the magazine relatively to the loom, bolts 54 holding the adjustment.

75 The rear part of the loom frame carries a sup-

port 75 having a hook 76 at the forward end thereof which as shown in Fig. 5 is positioned to engage the foot 45 of the magazine and prevent forward motion thereof to the left toward the lay from the dotted line position shown in Fig. 5. 5

When the magazine is in use in the full line position shown in Fig. 5, it will supply the selected reserve bobbin in the usual manner to permit transfer to the shuttle S which happens to be exhausted and on the magazine side of the 10 loom in the single shuttle box 31. Under these conditions the loom operates as does an ordinary 4x1 bobbin changing loom, the old bobbin being expelled through the slot 35 and the new bobbin being inserted into the shuttle. The links 60 and the rod 62 supported by the arch 63 and brace 64 assist in positioning the upper part of the magazine.

When it is desired to move the magazine to an inoperative position the bolts 54 are removed 20 so that the magazine may be slid along the rod 62 away from the center of the loom to the dotted line position of Fig. 1, after which the magazine is swung around rod 62, clearing the arches, to the dotted line position shown in Fig. 25 5. The magazine will come to rest with the foot 45 as already described resting on the support 75 and against the hook 76. Thereafter, as the loom is operated non-automatically the magazine will be held behind the lay, being supported 30 at the front end by the links 60 which are suspended from the rod 62, and at the rear end by the element 75. During the sliding of the magazine along rod 62, the foot 45 rests on the stand 46 to support the magazine until the latter 35 is ready to be swung rearwardly.

The purpose of swinging the magazine to the position shown in Fig. 4 is to permit the use at that end of the loom of a second gang of shuttle boxes designated generally at 80 and employing four shuttle cells each having its binder 81. A shuttle pressure relieving mechanism indicated generally at 82 may be employed, this mechanism operating generally along the principles set forth in Santon Patent No. 2,025,906 45 and being constructed more specifically as shown in co-pending application Serial No. 59,253 filed by Darwin.

In order to adapt the lay for the use of the gang 50 of boxes 80 I employ a plate 85 bolted as at 86 50 to the lay end 30 and having a groove 87 to receive a tongue 88 on the gang 80. A similar plate 89 having a groove 90 may be located permanently to the lay at the inner end of the gang 80, or at the left as viewed in Fig. 2. It is to 55 be understood that when the loom is operating automatically as set forth in full lines in Figs. 1 and 5, plate 85 will not be on the lay since the upwardly extending horn 92 thereon would interfere with the rear part of the magazine as the 60 lay beats forwardly.

The gang of boxes 80 is mounted on a box rod 95 which extends through a sleeve 96 sliding on the rocker foot 97 shown at the bottom of Fig. 2. A box lifter chain 98 similar to chain 22 and 65 controlled by the Knowles head not shown is connected to the sleeve at 55 and through the sleeve exerts an up force on spring 56 surrounding rod 95. The boxes are shown in their highest position in Figs. 2 and 5 so that the lowest cell aligns 70 with the shuttle race 20. A rod 99 depends from a horizontal ledge 100 of the lay end 30 and extends through a finger 101 on the sleeve 96. A coil spring 102 is interposed between a collar 103 on rod 99 and finger 101, acting at all times to 75

prevent the sleeve from rising and during upward shifting of the boxes arresting overthrow of the boxes under the influence of chain 98.

As shown in Fig. 5 the gang of boxes 80 can assume their highest position without interfering with the magazine due to the fact that the support rod 62 around which the magazine pivots is far enough to the rear so that the tops of plates 40 and 41 lie behind the shuttle boxes 10 when the lay is in the rear position, as indicated in dotted lines, Fig. 5. The mechanism for lifting the gang 80 may be of the usual construction, and of itself is not new.

When the parts are as shown in Fig. 4 the loom operates non-automatically pick and pick, the maximum capacity being seven shuttles and the loom capable of weaving a fabric having a single pick of a given weft as distinguished from the fabrics woven when the magazine is operative wherein at least two successive picks of a given color must be woven due to the single shuttle box 31.

When the loom is to be reconverted for automatic weaving the rod 95 together with the gang 80 of shuttle cells, is lifted upwardly out of the loom, the chain 98, however, remaining attached to the sleeve 96 and the rod 99 together with the spring 102 acting in normal manner. The relation of parts is such that even should the chain 30 98 move in response to pattern chain indications there will be no resultant interference because the chain and the parts operated thereby lie behind the spent bobbin can 105, shown in Fig. 3, and are below the bobbin chute 106 down 35 which the expelled bobbins move from the slot 35 to the can 105. In this way a considerable part of the mechanism which operates the gang of boxes 80 can be left on the loom when the latter is operating automatically.

From the foregoing it will be seen that I have provided simple means whereby a loom may be used either to operate automatically with a magazine to supply reserve bobbins, or non-automatically to weave a more elaborate pattern calling for shifting shuttle boxes at both ends of the lay. It will also be seen that when the magazine swings from operative to idle position it is clear of all parts of the lay, especially the shifting boxes 80 when the latter are in highest position. It will be seen that the plate 85 is readily removable when the loom is converted from pick and pick to automatic, thereby avoiding interference with the rear part of the magazine as the lay beats forwardly. Again, it will be seen that the removal 55 of the gang 80 together with its rod 95 permits the retention of the chain 98 and sleeve 96 which are located behind the bobbin can 105, in which position movement of the chain 98 will cause no damage. Also, the support 75 is so constructed that the hooked ends 76 thereof cooperates with the foot 45 to prevent movement of the magazine forwardly or to the left from the dotted position shown in Fig. 5 to a position where it might interfere with the lay as the latter 60 swings rearwardly. It should be noted that the means employed to support the upper part of the magazine as the latter swings from one to the other position also allows both vertical and horizontal adjustments of the magazine relatively to the lay when the loom is operated 65 automatically.

Having thus described my invention it will be seen that changes and modifications may be made therein by those skilled in the art without departing from the spirit and scope of the in- 70

vention and I do not wish to be limited to the details herein disclosed, but what I claim is:

1. In a loom, a lay, a reserve weft magazine, a foot forming part of the magazine, means to secure the foot to the frame of the loom in a position to support the magazine in transferring relationship with respect to the lay when the latter is forward, an additional support behind the lay to engage the foot when the magazine is in inoperative position, and a pivotal support 10 for the upper part of the magazine located behind the lay and around which the magazine is capable of swinging from the first named position to an inoperative position relatively to the lay, said pivotal support and additional support located 15 to maintain the magazine behind the lay.

2. In a loom, a lay, a reserve bobbin magazine, a pivotal support for the upper part of the magazine extending substantially parallel to the lay, connecting links between the pivotal support 20 and the magazine, securing means to position the magazine in transferring relation with respect to the lay when the latter is in foremost position, and additional support means behind the pivotal support positioned to cooperate with the 25 pivotal support to hold the magazine in a non-transferring position with all parts of said magazine behind the lay when the latter is in rear-most position.

3. In a loom, a lay, a magazine for reserve weft, 30 a pivotal support for the upper part of the magazine which assists in positioning the magazine in transferring relation with respect to the lay when the latter is in foremost position, and an additional support carried by the loom behind the 35 pivotal support, said magazine being capable of pivotal movement around the pivotal support into supporting relation with respect to said additional support, and the latter together with the pivotal support maintaining the magazine in an 40 inactive position behind the lay when the latter is in rear-most position.

4. In a loom, a lay capable of supporting either a single shuttle box or a gang of shifting shuttle boxes, a reserve weft magazine, means to support 45 the magazine in transferring relation with respect to the lay when the latter is forward and has a single shuttle box thereon to be located under the magazine, and additional means fixed with respect to the loom to support the magazine 50 in a non-transferring position, said additional support assisting in maintaining the magazine behind and clear of the lay when the latter is rearmost and when the shifting shuttle boxes 55 are in their highest position with respect to the lay.

5. In a loom, a lay capable of supporting either a single shuttle box or a gang of vertically shifting shuttle boxes, a reserve weft magazine, a pivotal support fixed with respect to the loom for 60 the upper rear part of the magazine, and two additional supports for the magazine, one cooperating with the pivotal support to hold the magazine in transferring relation with respect to the lay when the latter is forward and is provided 65 with a single shuttle box, and the other additional support cooperating with the pivotal support to maintain the magazine in a non-transferring position behind and clear of the lay when the latter is rearmost and when said shifting shuttle boxes 70 are in their highest position.

6. In a loom having a lay movable back and forth therein, a reserve weft magazine, and supporting means for the magazine fixed with respect to the loom to hold the magazine in an 75

- idle position behind the lay when the latter is in rearmost position, said supporting means including a pivot member around which the magazine can be moved to operating position, suspending links between the pivot member and the upper part of the magazine assisting in positioning the magazine for transfer relation with the lay when the magazine is in operative position; and said supporting means also including an element fixed with respect to the loom behind the pivotal connection to engage the lower part of the magazine to support the latter and also prevent the magazine from moving forwardly around the pivot member toward the lay.
7. In a loom, a lay, a magazine for reserve weft, a pivotal support for the magazine supported by the loom and located above and behind the lay, said support extending substantially parallel to the lay, links to connect the upper rear part of the magazine to the pivotal support, the latter and the links assisting in positioning the magazine in transferring relation with respect to the lay when the latter is in forward position and said links being slidable on the pivotal support to render the magazine capable of movement along said pivotal support away from the center of the loom when the magazine is being moved about the pivotal support from transferring position relatively to the lay to inactive position, and
- a fixed support on the loom behind the pivotal connection cooperating with the latter to maintain the magazine in an inactive position behind the lay when the latter is in rearmost position.
8. In a supporting structure for a reserve weft magazine of a loom having a lay movable back and forth therein, means forming part of the structure defining a sliding and pivotal support

for the upper part of the magazine assisting in holding the magazine in position of transferring relation with respect to the lay and along which the magazine can slide away from the loom and around which the magazine can swing from transferring to inoperative position, and an additional support cooperating with the first named support to hold the magazine in inoperative position behind the lay.

9. In a loom, a lay, a reserve weft magazine, supporting means for the upper part of the magazine extending substantially parallel to the lay, connecting means between said support means and the magazine, securing means to position the magazine in transferring relation with respect to the lay when the latter is in foremost position, and additional supporting means positioned to cooperate with said first supporting means and said connecting means to hold the magazine in a non-transferring position with all parts of the magazine out of the range of motion of the lay and of all parts carried thereby.

10. In a loom, a lay, a magazine for reserve weft, a support for the upper part of the magazine which assists in positioning the magazine in transferring relation with respect to the lay when the latter is in foremost position, and an additional support carried by the loom for said magazine, said magazine being capable of defined movement relative to said first support from operative to inoperative position and into supporting relation with said additional support, and said two supports cooperating to maintain said magazine in an inoperative position out of range of the lay and of all parts carried thereby.

IRVING H. VERRY.
